JAMES R. CLARK, OF ROCHESTER, NEW YORK, ASSIGNEE TO THE YAWMAN & ERBE MANUFACTURING COMPANY, OF NEW YORK, N. Y., A CORPORATION OF NEW YORK

YIELDING RETAINER FOR VISIBLE INDEX CARD HOLDERS

Application filed June 26, 1930. Serial No. 463,919.

In a copending application filed by the present applicant of even date herewith, Serial No. 463,918, there is shown, described and claimed mechanism for retaining card holders in a visible index tray yieldingly and facilitating their removal by relieving the retaining bar of the spring action by positive actuation of a spring-compressor. The present invention relates to mechanism which is of compact and simple construction and adapted to accomplish generally the purposes set forth in said copending application. In accordance with the present invention, however, instead of employing a spring-compressor for the purpose of relieving the retaining bar from the spring action, elements are provided which are so associated as to permit virtual elimination of all spring action so that the retaining bar may be free for displacement laterally under the influence of the card holders to be removed. In accordance with the principle involved the spring elements while normally operative to press the retaining bar yieldingly against the card holders may have their spring actually nullified at will by permitting them to take their natural set. More particularly, the preferred embodiment contemplates adjustable spring seats movable for the purpose of stressing the springs during the time that the retaining bar is to be effective and relieving this stress whenever it is desired to displace the retaining bar. A further object of the invention is to provide in combination with elements of the character set forth manually operable devices for thus stressing and relieving the stress on such spring elements. Still a further object is to provide means for yieldingly maintaining the springs normally in stressed condition, such means permitting, nevertheless, manipulation of the elements for the purpose of relieving the spring stress.

Reference is now to be had to the accompanying drawings for a detailed description of the preferred embodiment of the invention, in which drawings:

Figure 1 is a view in plan of a visible index tray, parts being broken away to show the retaining mechanism.

Figure 2 is a view similar to Figure 1 and

on a larger scale showing the retaining mechanism in position to relieve the stress on the holding springs.

Figure 3 is a view in transverse section through the tray shown in Figure 2 along the plane indicated by the line 3—3 of Figure 2.

Figure 4 is a fragmentary detailed view in section on the line 4—4 of Figure 2 showing the relationship of the retaining bar for the card holders, the shiftable spring seat and the finger pull for operating the spring seat.

The card tray *a* may be of any approved form having side flanges *a'*, *a''*, constituting channels in one of which may be disposed a bar *b* or the equivalent to position the card holders *c*. The other ends of the card holders *c* rest within the channel *a'* and the card holders are normally retained yieldingly against lateral displacement by the devices to be described. In order to remove a card holder from the tray it is desirable to permit it to be shifted towards the left as viewed in the drawings until its right-hand end is free from the flange *a''* after which it may be lifted out.

The retaining bar illustrated consists of an L-shaped stiff member *d*, the vertical flange on which may engage the ends of the holders *c* and the web of which may rest flatwise on the bottom of the tray within the channel *a'*. This retaining member, which may be formed as a stamping, may have struck up therein at intervals ears *d'* between which are disposed flat springs *e*. These springs seat on a longitudinally slid able bar *f* which may, in the interest of compactness, be nested with the retaining member *d*, the springs *e* being operatively interposed between the bar *f* and the flange of the retaining member. On the proximate edge of the bar *f* are spaced at intervals corresponding to the springs *e*, scallops *f'* which, if desired, may be substantially straight-lined or somewhat curved, as shown.

When the bar *f* is in normal position, that is in such position as to insure action of the springs *e* on the retaining bar *d* the springs *e* are stressed and engage the bar *f* generally either at points on its straight edge or adjacent to the ends of the scallops *f'*, as shown in Figure 1. At this time, the spring bar *d* resists yieldingly lateral movements of the

card holders *c*. One feature of the invention resides in the provision of means for automatically but yieldingly maintaining the bar *f* in this relationship. One such means may comprise a coiled spring *g* mounted within the tray *a* under the front plate *a*³ so as to be concealed. One end of this spring seats on a lug *g'* provided for that purpose and the free end engages the end of the bar *f* and urges the bar yieldingly in such direction as will maintain that relationship between the bar and the springs *e* which will insure such a degree of stress on the springs as may be desirable. When the bar *f* is moved longitudinally against the action of the spring *g* the scallops *f'* will be brought opposite their respective springs *e* so that these springs may virtually take their natural set at which time they are practically free from stress. To accomplish this, of course, the depth and width of the scallops must be apportioned to the springs and the relief desired. Since the bar *f* seats at the bottom of the channel *a'* it may be reciprocated in a straight line. A finger pull *h* may be engaged with the bar *f* to facilitate such reciprocation, a slot *a*⁴ in the flange *a'* being provided to permit free movement of the finger pull within the desired limits. When the stress on the springs *e* has been thus relieved with the parts in the relative positions indicated in Figure 2, it will be evident that the retaining bar *b* may be moved laterally with virtual freedom by moving any one or more of the card holders laterally to the left as viewed in the drawings. After the holders have been removed and pressure is released from the finger pull *h* the spring *g* will at once reciprocate the bar *f* in the opposite direction with sufficient force to return it to such relation with the springs *e* as will again give their predetermined stress to hold the retaining bar yieldingly against displacement.

Changes in the form of the elements, substitution of equivalents and reversal of parts will suggest themselves to one skilled in the art but any such departures are to be deemed within the invention so long as they accomplish the same purpose in accordance with the general principles set forth and fall within the appended claims.

What I claim is:

1. In combination with a tray having channels along its side edges, transversely disposed rigid members engaged with the channels, a retaining bar engaging the ends of said members, springs to urge the retaining bar yieldingly against said members, and means to remove the stress of said springs.

2. In combination with a tray having channels along its side edges, transversely disposed rigid members engaged with the channels, a retaining bar engaging the ends of said members, springs to urge the retaining

bar yieldingly against said members, and means to eliminate the spring action.

3. In combination with a tray having channels along its side edges, transversely disposed rigid members engaged with the channels, a retaining bar engaging the ends of said members, springs to urge the retaining bar yieldingly against said members, and means to change the seats for said springs to reduce their stress. 75

4. In combination with a visible index card tray and rigid card holders mounted therein, channels along the edges of the tray in which the ends of the card holders are disposed, a bar mounted at the bottom of one of the channels and presenting spring seats, springs engageable with said seats, a retaining bar engaged by said springs and normally pressing against the ends of said card holders, and means to move the first-named bar to change 80 the spring seats whereby the stress of the springs may be varied. 85

5. In combination with a visible index card tray and rigid card holders mounted therein, channels along the edges of the tray in which the ends of the card holders are disposed, a bar mounted at the bottom of one of the channels and presenting spring seats, springs engageable with said seats, a retaining bar engaged by said springs and normally pressing against the ends of said card holders, and means to move the first-named bar longitudinally to change the spring seats to vary the stress of the springs. 95

6. In combination with a visible index card tray and rigid card holders mounted therein, channels along the edges of the tray in which the ends of the card holders are disposed, a bar mounted at the bottom of one of the channels and presenting spring seats, springs engageable with said seats, a retaining bar engaged by said springs and normally pressing against the ends of said card holders, means to move the first-named bar longitudinally to change the spring seats to vary the stress of the springs, and yielding means to maintain 100 said first-named bar in predetermined position. 105

7. In combination with a visible card index tray having channels along its side edges and rigid card holders disposed therein, a retaining bar for the card holders disposed within one channel, springs engaging the retaining bar to urge it yieldingly against the card holders and a second bar disposed within said channel and on which said springs seat, said bar having relatively high and low points to engage each spring and means to move the bar to bring said high or low points selectively into engagement with the respective springs to vary their tension. 115 120

8. In combination with a tray having channels along its side edges and rigid members extending transversely of the tray and mounted within said channels, a retaining 125 130

bar engaging the ends of said members to hold them against lateral displacement, means to press the bar yieldingly into engagement with said members, and means to remove the pressure of said means from the bar.

This specification signed this 24 day of June, A. D. 1930.
